UNITED STATES PATENT OFFICE

2,563,619

PAPERBOARD CARTON CAPABLE OF
HOLDING LIQUIDSWilliam A. Ringler, Wayne, Pa., assignor to The
Gardner Board and Carton Co., a corporation
of Ohio

Application June 13, 1945, Serial No. 599,157

1 Claim. (Cl. 229—37)

1

There has hitherto been in certain fields a development of paperboard cartons for holding liquids. The cartons to which I refer are folding paperboard cartons in the sense that they are made up by the carton manufacturer by printing, cutting and scoring paperboard and tubing the blanks, the structures being sent to the user in the knocked-down condition. So far as I am aware, however, the practice in forming liquid carrying cartons has entailed erecting the tubed structure, forming an ordinary seal-end closure on one end, and then dipping the carton bodily in a bath of liquid-proofing substance so as to coat it within and without. Since these last operations can be performed economically only in the plant of the carton user, the development has entailed the purchase and operation of expensive and complicated machines by the user.

One object of the present invention is to provide a factory-made folding carton which will be capable of holding liquids, but which requires for setting up only the simplest form of carton closing devices. Specifically, my cartons do not require to be dipped. They may even be set up by hand operations of simple character and with simple tools; and one form of my structure requires no mechanism for setting up beyond a means to apply heat for rendering a thermoplastic adhesive tacky while the parts are held in closed position.

In the development of liquid holding cartons as outlined above, the bottom closure was effected prior to the dipping operation, the top closure being of another type or form. In general, these top closures have been splash proof but not liquid tight nor hermetically sealed. It is an object of my invention to provide cartons having the advantages mentioned above but sealable on both ends with equally liquid-tight results.

In the known liquid carrying cartons, water-proofed by the dipping operation to which I have referred, a relatively slight amount of handling or distortion, as an accidental bump upon the corners of the carton, serves to destroy the seal and impair or destroy the ability of the structure to carry liquid. It is an object of my invention to provide a construction capable of being handled roughly and in particular of being bumped on the corners without destruction of the seal.

While I have stressed the liquid carrying feature of my cartons, it will be understood that they need not necessarily be used for liquids, but have utility wherever an hermetic seal is required, such as would be inherent in a liquid-tight structure. Thus my cartons and closures are of value where

2

moisture resistance is required as well as where the problem is not or is not alone one of preventing the escape of liquids or moisture from the contents, but also involves protecting the contents from external conditions or liquid or moisture.

The several objects of my invention which have been outlined above or will be set forth herein-after or made clear to one skilled in the art upon 10 reading these specifications, I accomplish by that construction and arrangement of parts and in that procedure of which I shall now describe certain exemplary embodiments. Reference is made to the drawings wherein:

15 Figure 1 is a partial plan view of a blank for one form of my carton showing the inside surface of the blank.

Figure 2 is a similar partial plan view of the same blank showing its outside surface.

20 Figure 3 is a partial perspective view of a tubed and erected structure made from the blank of Figures 1 and 2 showing it in a stage of partial closure.

Figure 4 shows the carton in a succeeding stage 25 of closure.

Figure 5 shows the carton with the closure complete.

Figure 6 is a partial sectional view of the closed carton taken along the line 6—6 of Figure 5.

Figure 7 is a partial sectional view of the closed 30 carton taken along the line 7—7 of Figure 5.

Figure 8 is a partial plan view of a blank for a modified form of my carton and in particular one having a pouring spout construction. This 35 figure shows the outer surface of the carton blank.

Figure 9 is a fragmentary plan view of that portion of the carton having the outer member of the pouring spout, this view being of the inner surface of the carton.

40 Figure 10 is a partial perspective view of a carton formed from the blank of Figure 8 and closed; and it shows the operation of the pouring spout.

Figure 11 is a perspective view of a pressure element which I may employ in sealing cartons.

Figure 12 is a partial plan view of the blank for yet another form of my carton.

Figure 13 is a partial plan view of a carton 50 blank embodying some of the features of the blank of Figure 12, but incorporating additional features.

Figure 14 is a perspective view of a modified form of pressure element which I may employ.

55 In all of the various views, I have shown but

one end of the carton. It will be understood that the other end of the carton may have a similar closure in the sense of any of the closures herein illustrated and described, or it may have an entirely different closure such as any of the known closures in the folding carton art, depending upon the requirements of service for the carton.

It will be understood that for some uses a liquid-tight closure upon one end of a carton will suffice.

It may be noted further that certain of my closures are particularly appropriate for sealing by means of a mandrel and hence are particularly appropriate for the first closure of a carton. One style of closure herein described does not require an interior mandrel and hence is particularly appropriate for the last formed closure of a carton, though it may be used for both closures if desired.

Referring to Figures 1 and 2, I have shown a carton having body walls 10, 11, 12 and 13 in articulation. Closure flaps 14, 15, 16 and 17 are articulated not only to the end of the body walls but also to each other as shown, score lines being indicated by dotted lines. A glue flap 18 is articulated to one of the body walls 13 and a prolongation of it 19 is articulated to one of the closure flaps.

In the particular style of carton shown in blank form in Figures 1 and 2, I provide an internal abutment partition for sealing purposes. In a copending application Serial No. 574,838 filed January 27, 1945, entitled Sift-Proof Carton and Means and Method for Sealing It, now abandoned, I have described a similar abutment partition for use in making a second closure on otherwise ordinary seal end cartons to prevent sifting. The glue flap 18 is made about half as wide as an opposite wall of the structure to which it will be attached when the structure is tubed, and the abutment partition member 20 is articulated to it. A glue flap 21 is articulated to the outer edge of the abutment partition. The abutment partition is made wide enough to extend across the erected carton.

With appropriate imposition of adhesive to the glue flaps 18, 19, 21, or to the walls to which they are adhered, the carton blank of Figures 1 and 2 may be tubed in the ordinary fashion as by bending it upon score lines 22 and 23 or other appropriate score lines, as will readily be understood by the skilled worker in the art. The glue flap 18 becomes adhesively secured to the wall 10, while the glue flap 19 becomes adhesively secured to the flap 14. The glue flap 21 on the abutment partition is secured to an intermediate portion of the wall 12. The resultant structure is a flat, tubular, knocked-down carton which, when squared up, will present an internal partition member acting as an abutment as indicated in Figure 3.

My sealing flaps are articulated together, as indicated, and are provided with score lines for diagonal folding in certain of the flaps, giving a bellows construction to the closure. While I have illustrated a carton which is square in cross-section, it will be understood that I am not limited to any particular shape and that the walls and closure flaps may be variously configured to provide cartons of different cross-sectional shapes. One pair of the closure flaps, e. g. 14 and 16 are, however, of a size and shape to cover the entire end of the carton within the limits of reasonable cutting accuracy. They may be slightly shortened in the direction of the length of the body walls, but best results are secured

by having them accurately cut and scored in the cross-sectional shape and size of the carton end.

The two remaining flaps are provided with diagonal scores 24 and 25 upon which they may be bent as aforesaid. These scores do not meet at the mid-section of the flaps, but instead, by means of cut lines, I provide for the formation of small, central tabs 26 and 27, as shown. The upper section of the flaps 15 and 17, beyond a prolongation of the score lines 24 and 25 are cut away as shown.

I employ a combination of the bellows folding construction to which I have referred and a particular kind of adhesive union to provide an end closure which is both liquid-tight and exceedingly strong. It is also without weakness or openings at the corners of the carton and hence will withstand blows there without leakage. The type of adhesive union which I employ requires the placement of adhesive on both faces of the blank. In Figure 1 and 2, I have shown adhesive coated areas in shaded lines. It will be noted that on the inside of the blank the adhesive preferably covers the major part of the areas of flaps 15, 16 and 17, but is omitted from flap 14 because this is the flap which will be folded first and will form the inside of the closure. On the outside surface of the flap portion of the blank, I impose adhesive preferably as shown in the shaded areas in Figure 2. As a safety factor in this carton, I have shown adhesive so applied to the various flaps as to result in bringing adhesive against adhesive in the closure formation. Hence, the outer surface of flap 14 is substantially covered. So also are the two side portions of flap 15; but the rectangular tab 26 of this flap does not require to be covered. Flap 16 is coated in those areas which will be lapped by the bellows folds in the final closure and flap 17 is similarly coated including tab 27.

The adhesive may be any suitable one, preferably thermoplastic. It may be applied by a printing operation performed upon the blanks.

Figure 3 shows the first stage in forming a closure on the erected carton. The flap 14 has been folded inwardly causing portions of flaps 15 and 17 to fold bellows-wise inside other portions of these same flaps, one of which portions is shown at 15a in the figure. The next operation is that shown in Figure 4 where the opposite flap 16 has now been folded down to close the end of the carton and to overlie flap 14. This results in a further folding of the flaps 15 and 17 along diagonal lines forming three-thickness ears 17b and 15b beyond which the tabs 27 and 26 extend. The ultimate condition of the closure is illustrated in Figure 5 where the ears 17b and 15b have been folded inwardly to overlie the top closure. In the shape of the carton shown, this results in an overlapping of the tabs 26 and 27 in the mid-section of the closure, as illustrated in Figures 5 and 6.

The cross-sectional view taken along the line 7-7, as in Figure 7, shows the interfolded bellows portions. It will be noted that my closure is characterized by continuous and imperforate paperboard or boxboard at the corners. The bellows folded portions are tightly compressed. All portions of the closure are in adhesive union, one with another. Such adhesive union is readily obtained by exerting pressure on the outer side of the closure, the abutment partition 20 serving to support the closure parts within the container to permit such pressure to be exerted and to be effective. The parts may be brought to interfolded

condition, as illustrated in Figure 5, before the thermoplastic adhesive is softened or rendered tacky, and heat may be applied to soften the adhesive after the interfolding of the parts, or heat may be applied during the interfolding. In either event the parts are held together under adequate pressure until by cooling the adhesive has been set. Thus a pressure element may first be heated and then cooled or one element may be employed to soften the adhesive and render it tacky and another unheated element may be employed to maintain the parts in folded condition under pressure until the adhesive has cooled and set.

In Figure 11 I have shown a pressure element of a shape suitable for holding the parts in assembled relationship either during heating or cooling or both. While this element has been illustrated with its configured face upwardly, it will be understood that it will be reversed and brought down upon the top of a carton for effecting the top closure. The pressure element is indicated generally at 28. It has raised pressure faces 29 and 30 for contacting the outer face of flap 16 between the ears. It has recessed pressure faces 31 and 32 for contacting and pressing the bellows folded ears 17b and 15b; and it has a centrally located somewhat less recessed portion 33 for contacting and pressing the superposed tabs 26, 27. It is a convenient form of pressure and/or temperature control device for use as such with a carton having an interior abutment partition 20, but in cartons not employing such an abutment partition, it may be used with an internal flat or substantially flat mandrel member, as will be evident. Where but one closure is to be formed by the means and method thus far disclosed, the interior abutment partition 20 need not extend throughout the length of the carton. Also it may be noted that the bifurcated mandrel disclosed in my copending case mentioned above may be employed in a partition carton for effecting the closure at the other end, and this is true whether the closure at the other end be of any of the forms set forth herein or of some other form.

In Figures 8, 9 and 10, I have shown a blank and carton embodying a pouring spout. Here body walls 34, 35, 36 and 37 and a glue flap 38 are in articulation with each other and with flaps 39, 40, 41, 42, and a glue flap 43, which are also in articulation with each other. In flap 39 I have formed by a U-shaped cut line and a transverse score a contained flap 44. Closure flap 41 is provided with a lifting tab 45 articulated at a point inwardly of the flap end by means of a score line and otherwise severed from the flap by cut lines as shown. It extends beyond the end of the flap 41 and is provided with articulated sections 46 and 47.

The shaded area in Figure 8 illustrates the placement of adhesive on the exterior of the blank; and it will be noted that the placement is similar to that shown in Figure 2 excepting that adhesive is omitted about the cut lines demarcating the contained flap 44 while an area of adhesive is carried down onto wall 34 around the contained flap, as at 48. On the inside of the blank the adhesive placement is generally similar to that illustrated in Figure 1 excepting that adhesive is omitted on the lifting tab 45, 46, 47 in an area 49 responding to the area about the cut line demarcating the contained flap. Adhesive is applied, however, longitudinally centrally of the articulated portion 46.

When this carton has been closed, as herein-

above described, the lifting tab in the portion 45 becomes adhered to the contained flap 44. Portions 46 and 47 lap over wall 34, as shown in dotted lines in Figure 10, the first of these articulated sections being adhered to the wall 34, but the other being free. When the free section is grasped by the fingers and the closure element raised, as shown in solid lines in Figure 10, the contained flap comes up with the lifting tab, leaving a reclosable pouring opening 44a.

In connection with the blank of Figure 8, I have not illustrated the interior partition abutment, but it may be provided if desired. Otherwise, the closure illustrated in Figure 10 is preferably made over an interior mandrel by means of some such exterior pressure element as that shown in Figure 11, which may be provided with an additional means for folding sections 46 and 47 of the lifting tab over onto wall 34 and effecting the described adhesive union.

In Figure 12 I have illustrated yet another type of carton having body walls 50, 51 and 52 in articulation, the first and last of these having articulated to them partial body wall members 53 and 54 so dimensioned that when the carton is tubed, they will lap in part to form the fourth body wall with a central seam. Flaps 55, 56, 57 are articulated to the first three mentioned body walls and to each other, while partial flaps 58 and 59 are articulated to partial walls 53 and 54 and bear the same relation to each other. It will be seen that flaps 55 and 57 are shorter than the remaining flaps. They are provided with diagonal fold lines 60 and 61 similar to the fold lines 24 and 25 of Figure 1. The tabs 26 and 27 have been omitted, however, as will be seen. The configuration of flaps 55 and 57 is such that when closure is made substantially as hereinabove described, the ears are not of three thicknesses but of two, the folded over portions coming together along a line disposed centrally of the ears. From the standpoint of liquid-tightness, a closure of this type depends upon the parts being brought together and pressed tightly in accurate relationship, and to promote this, I score the flaps along the various lines to soften the board at these lines and assist the various board lines to conform to each other. Thus I have shown longitudinal score lines 62, 63 and 64 in the flap and half-flaps 56, 58 and 59, together with diagonal score lines 65 and 66. Score lines 62 and 64 are so placed as to lie along the edges of the overlap between flaps 58 and 59. Horizontal scores 67 may also be provided if desired. Flaps 55 and 57 may have score lines 68 placed to correspond to the meeting edges of the bellows folds hereinabove mentioned. In sealing such a carton (as will preferably be done over an internal mandrel), I have preferred to use a pressure element, such as that shown at 69 in Figure 14. Here I have indicated raised sections 70 for contacting superposed flaps 56, 58 and 59. Centrally there is an area 71 which, because of the thickness of the overlap between partial flaps 58 and 59, will be somewhat depressed.

Further depressed areas 72 are provided to subject the folded over ears to pressure. Slightly raised, narrow elements 73 may be provided to exert pressure on the ears at the lines where the bellows folds come together to press the board as well as the applied and softened adhesive into hermetic union along these lines.

In Figure 13 I have illustrated a somewhat similar construction with the modification that the lines along which the bellows folds of the ears

come together are made elongated and sinuous to the extent of increasing the safety factor of the seal along these lines. Similar parts have been given the same index numerals, but it will be seen that the upper edges of flaps 55 and 57 have been made sinuous as at 14 and 15. It will be clear how these parts interfit when the bellows folds are made. The pressure block of Figure 14 may be modified for this carton by eliminating the narrow pressure ribs 13. Otherwise the operation of folding and sealing will be the same.

As to the application of adhesive to the blanks of Figures 12 and 13, it may be essentially the same on the inside of the carton as that shown in Figure 1. Thus substantially all portions of flaps 55, 56 and 57 may be coated with adhesive. The flap formed by the partial flap members 58 and 59 may be left uncoated to form the inside surface of the closure. On the outside of the carton blank, it will be necessary to apply adhesive to the upper semi-triangular portions of the flaps 55 and 57 in order to cement these down to the flap 56. Corresponding portions of that flap may likewise be covered with adhesive if desired. While, where I have illustrated adhesive application, I have shown in such areas as to result in bringing adhesive against adhesive in the folded closure, it will be understood that with an adequate application of adhesive, a coated board portion may be brought against an uncoated board portion with the obtaining of an adequate bond. To this extent the application of adhesive both inside and outside the carton may be modified. As to the board from which the carton is made, it may be any suitable, bendable paperboard or boxboard. Needless to say, it may be liquid-proof in itself or treated as may be desired with liquid-proofing substances.

Modifications may be made in my invention without departing from the spirit of it. Having thus described my invention, what I claim as new and desire to secure by Letters Patent is:

A carton comprising a tubular body rectangular in cross section and having body walls in articulation with each other, four integral end

closure flaps articulated to the end of said body walls and interconnected to each other along fold lines extending throughout their common lengths, alternate ones of said closure flaps dimensioned to correspond to the cross-sectional dimensions of said body, the remaining two closure flaps being of lesser area than said first mentioned flaps and divided by diagonal score lines into three parts each, namely, a base portion 10 lying along the base of each of said remaining flaps, and a pair of wing portions lying along opposite sides of each of said remaining flaps and articulated to said base portions along said diagonal score lines, said diagonal score lines starting at the outermost corners of said remaining flaps at the bases thereof and extending diagonally through said remaining flaps to the free edges thereof, the base and wing portions of each of said remaining flaps when folded bellows-wise forming ears foldable over said first mentioned flaps when said first mentioned flaps are in superposed condition, the wing portions in each of said remaining flaps being coextensive with each other and with the said base portions.
